[57] CLAIM

The ornamental design for “coin cup holder”, as shown.

DESCRIPTION

FIG. 1 is a front and right side perspective view of the coin cup holder showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken line showing of a coin cup in FIG. 1 is for illustrative purposes only and forms no part of the claimed design.
